(57) **CLAIM**

The ornamental design for an animal bed with cover, as shown and described.

DESCRIPTION

FIG. 1 is bottom perspective view of a first embodiment of the animal bed with cover wherein the cover is permanently attached.

FIG. 2 is a front view of the animal bed with cover wherein the cover is permanently attached.

FIG. 3 is a back view of the animal bed with cover wherein the cover is permanently attached

FIG. 4 is a side view of the animal bed with cover wherein the cover is permanently attached.

FIG. 5 is a second side view of the animal bed with cover wherein the cover is permanently attached.

FIG. 6 is a bottom view of the animal bed with cover wherein the cover is permanently attached.

FIG. 7 is a top view of the animal bed with cover wherein the cover is permanently attached.

FIG. 8 is a top perspective view of the animal bed with cover wherein the cover is permanently attached.

FIG. 9 is a bottom perspective view of a second embodiment of the animal bed with cover wherein the cover is removably attached.

FIG. 10 is a front view of the animal bed with cover wherein the cover is removably attached.

FIG. 11 is a back view of the animal bed with cover wherein the cover is removably attached

FIG. 12 is a side view of the animal bed with cover wherein the cover is removably attached.

FIG. 13 is a second side view of the animal bed with cover wherein the cover is removably attached.

FIG. 14 is a bottom view of animal bed with cover wherein the cover is removably attached.

FIG. 15 is a top view of the animal bed with cover wherein the cover is removably attached.

(Continued)

FIG. 16 is a top perspective view of the animal bed with cover wherein the cover is removably attached; and, FIG. 17 is a top perspective view of the animal bed with cover wherein the cover is removably attached and wherein said cover is detached and rolled into a sleeve. All broken lines in the drawings depict environmental structure and form no part of the claimed design.
